SOUND FILM REPRODUCING SYSTEM

Emanuel C. Manderfeld, Berkeley, Calif., assignor
to Western Electric Company, Incorporated,
New York, N. Y., a corporation of New York

Application January 26, 1944, Serial No. 519,742

7 Claims. (Cl. 179—100.3).

This invention relates to sound film reproducing systems and more particularly to improvements in the method of and means for obtaining sound reproduction from film sound tracks of different widths in the same reproducing apparatus.

It is the object of this invention to provide a sound film reproducing apparatus wherein reproduction from sound tracks of different widths may be obtained without necessitating lateral movement of the film or lateral movement of the optical elements of the reproducing system.

A feature of the invention lies in the provision of a combination of means for producing an acoustically modulated light beam corresponding to the widest sound track to be reproduced, a light sensitive device having a pair of cathodes disposed in oblique relation to the light beam with equal areas thereof projecting onto each of the cathodes, and means for shifting the light beam in a direction normal to its longer dimension and masking all but that portion thereof corresponding to a sound track of reduced width to locate equal areas of the reduced light beam on each of the cathodes of the light sensitive device.

In sound film reproducing optical systems it is desirable that the optical elements and the elements defining the film path through the optical system be supported on fixed mountings. As is well known, the width of a standard sound track on a sound picture film is approximately 100 mils. With the introduction of 100-mil push-pull sound tracks, some modification was required to adapt existing apparatus to reproduce both the 100-mil standard and the 100-mil push-pull sound track. This modification involved the introduction of a central septum in the optical system, the use of a double cathode light sensitive device and switching means in the circuit for the light sensitive device substantially as disclosed in United States Patent 2,094,063, September 28, 1937, to J. C. Davidson. This modification, however, did not require the provision of means for shifting the lateral position of the lens elements or of the lateral position of the film. With the introduction in recording processes of a 200-mil push-pull sound track it became necessary to provide a studio reproducer capable of reproducing from 100-mil push-pull or standard tracks and from a 200-mil push-pull track. Reproducers supplied for this purpose include a laterally slideable mounting for the elements of the optical system. The use of a mounting of this type necessitates the provision of movement limiting

stops to insure the accurate location of the optical center line with the center line of each type sound track on the film which, together with the slideable mounting, adds considerably to the cost of manufacture and introduces the disadvantage that the adjustment of the stops must be frequently inspected during operation to insure efficient operation.

By means of the reproducing system in accordance with this invention, different width sound tracks may each be efficiently reproduced in the same apparatus by a novel arrangement of the elements of the reproducing system involving no lateral adjustment of the film or the optical elements of the system.

The invention will be more readily understood by reference to the accompanying drawing in which:

Fig. 1 is an illustration in perspective of a reproducing apparatus embodying the invention;

Fig. 2 is a view of the reproducing system of Fig. 1 from the objective lens photoelectric cell with the light beam shifted to a different scanning position;

Fig. 3 is a partial view of the reproducing system of Fig. 1 showing the position of the light beam and an auxiliary masking means for reproduction of 100-mil standard sound track; and

Fig. 4 discloses an alternative method of shifting the light beam in a direction normal to its longer dimension.

Referring to Fig. 1, the reproducing optical system shown therein represents a well-known rear-scanning optical system in which a collector lens 1 images the filament of light source 2 at condenser lens 3. Condenser lens 3 focusses the aperture of collector lens 1 at the plane of film F. The aperture of the condenser lens 3 is focussed, by means of a relay lens 4, at an objective lens 5. The objective lens 5 produces an image of the sound track on film F at a scanning slit 6 in masking plate 7. A light sensitive device 8 provided with a pair of cathodes 9 and 10 is disposed behind the plate 7.

The section of film F shown as passing through the optical system is provided with a 200-mil push-pull sound track which modulates the light beam projected to slit 6 in plate 7. Scanning slit 6 is provided with a center septum 11 to mask the dividing line between the halves of the push-pull track. The modulated light beam after passing through the slit 6 is received by the light sensitive device 8 with the two cathodes 9 and 10 each receiving a light beam modulated by one half of the 200-mil push-pull track.

The light sensitive device 8 is disposed in the light beam in oblique relation thereto, that is, the axis of the cathodes 9 and 10, as represented by line 12, is turned in the plane of the cathodes through an angle θ with respect to line 13 normal to the light beam.

The light sensitive device 8 is included in a reproducing circuit in a well-known manner to give push-pull reproduction of the 200-mil push-pull sound track.

If it is desired to reproduce from a 100-mil push-pull sound track as shown on section F₂ of the film it is necessary only to shift the light beam in a direction normal to its longer dimension to a position as shown in Fig. 2, in which the light beam is projected through scanning slit 14 in plate 7. Scanning slit 14 is one-half the length of scanning slit 6 so that the portion of the light beam unmodulated by a sound track is masked by the plate 7. Due to the oblique relation between the light beam and the cathodes of the light sensitive device, equal areas of the reduced width light beam corresponding to the 100-mil sound track will be received by each of the cathodes 8 and 10 for push-pull reproduction. The slit 14 is provided with a center septum 15 similar to the septum 11 provided in slit 6.

A means provided for producing movement of the light beam in a direction normal to its longer dimension comprises an adjustable reflector 16 interposed in the modulated light beam between the objective lens 5 and the masking plate 7. The reflector 16 is secured to a shaft 17 which may be rotated by means of a knurled knob 18. The shaft 17 is provided with a disc 19 having a projection 20 which is movable to either one of two limiting stops 21 and 22.

If the sound track shown on section F₂ of the film is a standard 100-mil sound track, it may be reproduced in the same reproducing system by the arrangement as shown in Fig. 3, in which the light beam is directed to scanning slit 6, as in Fig. 1, but in which means are provided at slit 6 for masking the unmodulated portion of the light beam. The remaining portion of the light beam corresponding to a 100-mil standard sound track is projected to one cathode only of the light sensitive device 8. A masking means provided comprises a mask 24 slidably mounted in block 25. A machine screw 26 secured in mask 24 extends through slot 27 in block 25 to limit the movement of the mask in either direction of movement.

Fig. 4 discloses an alternative means for registering the modulated light beam with either one of the scanning slits in plate 7. In this arrangement, a reflector 30 is fixedly mounted in the optical system. The sound track on the film is scanned longitudinally of the film over a distance sufficient to produce an image at plate 7 of sufficient size, as represented by the dotted lines, to cover substantially the entire surface of this plate. By means of a movable mask 31 the proper aperture may be readily selected for 200-mil push-pull, 100-mil push-pull or 100-mil standard reproduction. In the drawing, the mask 31 is positioned to permit reproduction from a 100-mil standard sound track as slit 14 and one-half of slit 6 are masked. Movement of mask 31 to the right will open slit 14 and completely mask slit 6 to permit reproduction only from a 100-mil push-pull sound track. Movement of mask 31 to the left from the position shown in the drawing will completely open slit 6 and mask slit 14 to permit reproduction only from a 200-mil push-pull sound track.

While for the sake of simplicity in the drawing the film F is shown as following a straight path through the optical system, it will be understood that the film may follow a curved path through the optical system as defined by a rotatable film supporting drum commonly employed in sound film reproducers.

It is common practice in optical systems of the type disclosed herein to employ either spherical or cylindrical relay lenses between the plate 7 and the photoelectric cell to focus the rear aperture of objective lens 5 on to each of the photoelectric cell cathodes 9 and 10. However, as the exclusion of relay lenses for this purpose in the drawing accompanying this specification permits of a clearer disclosure of the position of the photoelectric cell with respect to the modulated light beam, such lenses have been omitted from the drawing.

20. What is claimed is:

1. The combination of means producing an acoustically modulated light beam, a light sensitive device having a pair of cathodes obliquely disposed in said light beam to receive equal areas thereof on each cathode, means for moving said light beam over said cathodes in a direction normal to the longer dimension of said light beam and means for masking said light beam from an end thereof to again project equal areas of said 25 reduced light beam on to each of said cathodes.

2. The combination of means producing an acoustically modulated light beam, means for shifting said light beam in a direction normal to its longer dimension to either of two paths 30 for reproduction, means for masking a portion of the length of said light beam in one of its shifted positions and a light sensitive device provided with a pair of cathodes disposed in oblique relation to said beam whereby said cathodes each 35 receive an equal fractional area of said light beam in either position of said beam.

3. A sound film reproducing system comprising means for producing an acoustically modulated light beam, masking means interposed in the path of said beam and provided with a pair of displaced parallel scanning slits of different lengths, means for shifting said light beam in a direction normal to its longer dimension to present said light beam at either one of the scanning slits in said masking 45 means and a light sensitive device provided with a pair of cathodes disposed behind said masking means in oblique relation to the scanning slits therein.

4. In apparatus for selectively reproducing film 50 sound tracks of different widths, the combination of means producing an acoustically modulated light beam corresponding to the widest sound track to be reproduced, a light sensitive device provided with a pair of cathodes disposed in said light beam in oblique relation thereto with equal areas of said beam directed to each of said cathodes, means for shifting said light beam in a direction normal to its longer dimension and means disposed in said light beam in its shifted 55 position for masking all but that portion of said beam corresponding to a sound track of reduced width whereby equal areas of said reduced width beam are directed to each of said cathodes.

5. In apparatus for selectively reproducing film 60 sound tracks of different widths, the combination of means producing an acoustically modulated light beam, masking means interposed in said beam and provided with a scanning slit having its longer dimension substantially equal to the 65 width of a light beam corresponding to the widest 70 width of a light beam corresponding to the widest 75 width of a light beam corresponding to the widest

sound track to be reproduced and a second scanning slit having its longer dimension substantially equal to the width of a light beam corresponding to a reduced width sound track, means for alternatively directing said light beam to one or the other of the scanning slits in said masking means and a light sensitive element provided with a plurality of cathodes disposed behind said masking means in oblique relation to the scanning slits therein.

6. In a sound film reproducing system the combination of means for selectively reproducing film sound tracks of different widths comprising means for producing a substantially rectangular light beam corresponding to the widest sound track to be reproduced, an adjustable reflector interposed in the path of said beam for alternatively directing said beam along either of two paths, means interposed in one of said paths for limiting the longer dimension of said beam to correspond to the smallest width sound track to be reproduced and a light sensitive device having a pair of cathodes obliquely disposed in said light beam

in a manner to receive equal fractional areas of said beam on each cathode for each position of said light beam.

7. In apparatus for selectively reproducing film sound tracks of different widths, the combination of means producing an acoustically modulated light beam corresponding to the widest sound track to be reproduced, masking means interposed in said beam and provided with a scanning slit having its longer dimension substantially equal to the width of said light beam and a second scanning slit having its longer dimension substantially equal to the width of a light beam corresponding to a reduced width sound track, a light sensitive device provided with a pair of cathodes disposed behind said masking means in oblique relation to the scanning slits therein to receive on each of said cathodes an equal fractional area of said light beam from each scanning slit, and means for selectively masking one or the other of the slits in said masking means.
